(57) **CLAIM**

The ornamental design for a decorative and connectable display product, as shown and described.

DESCRIPTION

FIG. 1 is a perspective view of a decorative and connectable display product;

FIG. 2 is a front perspective view thereof;

FIG. 3 is a rear perspective view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a top plan view thereof;

FIG. 9 is a bottom plan view thereof; and,

FIG. 10 is a bottom plan view thereof showing multiple interconnections.

The broken lines depict environmental subject matter only and form no part of the claimed design.
